UNITED STATES PATENT OFFICE.

WILLIAM BAUM, OF NEW HAVEN, CONNECTICUT, ASSIGNOR TO THE NEW JERSEY CAR SPRING AND RUBBER COMPANY, OF JERSEY CITY, N. J.

DESIGN FOR A RUBBER SOLE.

SPECIFICATION forming part of Design No. 16,904, dated September 21, 1886.

Application filed August 5, 1886. Serial No. 210,130. Term of patent 7 years.

To all whom it may concern:

Be it known that I, WILLIAM BAUM, of New Haven, county of New Haven, and State of Connecticut, have invented a new and original Design for Rubber Soles, of which the following is a specification.

The accompanying photograph represents a bottom view of a sole of my new design.

This invention relates to the new ornamentation of the lower side of a rubber sole. The sole A is at its lower side, next the margin, surrounded by a projecting rounded bead, a. On the inner side of this bead are inwardly-projecting radial ribs b b. The inner part of the sole has series of projecting hexagon-shaped figures d.

I claim—

1. The design for a sole, consisting of the outer rounded bead, a, on its lower side, next the margin of the sole, substantially as shown. 20
2. The design for a sole, consisting of the outer rounded bead, a, on its lower side, next the margin, and of the radial ribs b b on the inner side of said bead, substantially as shown. 25
3. The design for a sole, consisting of the outer rounded bead, a, radial ribs b b on the inner side of said bead, and inner geometrical figures, d d, substantially as shown.

WILLIAM BAUM.
